UNITED STATES PATENT OFFICE.

JOSEPH WARREN CUTLER, OF ROCHESTER, NEW YORK.

CLOSURE FOR MAIL-CHUTES.

SPECIFICATION forming part of Letters Patent No. 744,724, dated November 24, 1903.

Application filed January 14, 1903. Serial No. 139,020. (No model.)

To all whom it may concern:

Be it known that I, JOSEPH WARREN CUTLER, of Rochester, in the county of Monroe and State of New York, have invented certain new and useful Improvements in Closures for Mail-Chutes; and I do hereby declare the following to be a full, clear, and exact description of the same, reference being had to the accompanying drawings, forming a part of this specification, and to the reference-numerals marked thereon.

My present invention relates to mail-chutes, and has for its object to provide an improved closure for the chute-openings of the various floors of a building in order that access to the chute may be controlled by authorized persons when desired; and it consists in certain improvements in construction and combinations of parts, all as will be hereinafter more fully described, the novel features being pointed out in the claims at the end of the specification.

In the accompanying drawings, Figure 1 is a sectional view of a mail-chute, showing my improvements, two mailing-openings being shown at different floors, one being open for receiving mail-matter and the other closed and locked. Fig. 2 is a front view of the mailing-section with the outer cover-plate of the casing removed. Fig. 3 is a horizontal sectional view on the line *a a* of Fig. 2. Figs. 4 and 5 are sectional views on the line *b b* of Fig. 2, showing the lid or door open and closed, respectively. Fig. 6 is a perspective view of the door operating and locking device.

Similar reference-numerals in the several figures indicate similar parts.

1 indicates a mail-chute of the ordinary construction having the usual glass plates 2 at the front and preferably made in separate sections and extending through the several floors of a building and terminating in a suitable box or receptacle at the lower end.

3 indicates the mailing-section, embodying a casing applied to the front of the chute, one being located at each floor and through which the mail-matter is passed into the chute, said casing having at its top the aperture 4 and below this an apron or depending plate 5 for preventing mail-matter descending from above catching or being retained.

6 indicates a plate having the flanges 7 at

the side and pivoted at 8 in the sides of the casing and at the lower end thereof, the upper end of said plate being bent rearwardly 55 to form a closure for the aperture 4 and in the present instance having attached a separate closing-plate 9, which may or may not constitute a sign containing the word "Closed" and indicating the condition of the chute-aperture. The plate 6 is bent at a slight angle between the pivotal point and the end above, as shown, and is provided with inwardly-extending lugs or projections 10, preferably stamped out of the metal some distance below the upper end.

11 indicates a cross-bar in the rear side of the plate, to which are attached the ends of the springs 12, the lower ends of the latter being connected to suitable studs in the casing 3, said springs serving to hold the plate normally in the open position shown in Fig. 1.

Other methods of constructing the door may be readily employed; but one such as I have shown, in which the pivotal point is arranged beneath it, is preferable, as any force offered to the door, such as may be exerted in an attempt to thrust it open, will be borne by the pivots and not by the locking devices.

Journaled at one end in a bearing in the casing is a shaft or arbor 13, the other end being preferably irregular in cross-section to form an engaging portion and having upon it a collar or thimble 14, journaled in an aperture in the casing and movable longitudinally 85 upon the arbor. The thimble 14 is provided with an arm in which is mounted a projection or pin 15, adapted to coöperate with suitable apertures 16, formed in the side of the casing, and said thimble is normally pressed outward to cause the engagement of the pin on one of the projections by a spring 17, encircling the arbor and arranged between the thimble and a cam or arm 18 thereon.

19 indicates a removable key or operating-handle having a recess adapted to fit the end of the arbor 13 and capable of a movement longitudinally of the arbor to disengage the thimble from the casing and permit the rotation of the arbor.

Mounted upon the arbor 13 are the arms or cams 18, preferably two, constructed, as shown, with a rounded portion or end 21, adapted to contact with the rear side of the

plate 6 and having the shoulders 22 and 23 arranged to contact with the outer plate 31 in the casing 3 to limit the movement of the arbor.

- 5 In order to close the aperture 4 in the casing and prevent the passage of letters into the chute, it is only necessary to insert the key 19 to disengage the pin 15 from one of the apertures and then turn the arbor, so that 10 the cam will occupy the position shown in Fig. 5, and then remove the key outwardly, when the spring 17 will again lock the arbor, the upper end of the plate 6 preventing access to the chute-aperture. By applying the 15 key and manipulating the arbor in the opposite direction the aperture will be opened, these operations being repeated when desired.

The projections 10 upon the plate 6 being located at a considerable distance below the 20 aperture 4 will effectually prevent the passage into the chute of papers or letters larger than those for which it is adapted, the serrations more effectually preventing the lateral movement of a package with a small end or 25 corner, as described more particularly in my previous patent, No. 430,626.

I claim as my invention—

1. The combination with a mail-chute having an aperture therein, a movable door for 30 closing the aperture and a spring for operating the door in one direction, of an arbor having a cam coöperating with the door to move it against the spring, a locking device for the arbor and a removable operating-key coöperating with the locking device to release the arbor when moved longitudinally thereof.

2. The combination with a mail-chute having a mail-receiving aperture and a door arranged to close the aperture, of a rotary arbor 40 separate from the door and having a cam thereon coöperating with the door to close it when moved in one direction and a locking device for holding the arbor and movable longitudinally thereof to secure and release it.

- 45 3. In a mail-chute, the combination with a casing having an aperture, a hinged door within the casing and adapted to close the aperture, of an arbor journaled in the casing having means coöperating with the door to oper-

ate it and a locking device for the arbor movable longitudinally thereof to secure it to the casing.

4. In a mail-chute, the combination with the casing having an aperture and a door for closing it, of the arbor coöperating with the door to close it and having an irregular-shaped 55 operating end, a locking device for the arbor and a removable operating device applicable to the arbor and adapted to coöperate with the locking device to release it. 60

5. The combination with the casing having the aperture and the door for closing it, of the arbor journaled in the casing and coöperating with the door to operate it, the locking-collar coöperating with the arbor and casing to secure the former and a removable operating device for the arbor adapted to coöperate with the locking-collar to disengage it from the casing. 65

6. The combination with the casing having 70 the aperture and the door for closing it, of the arbor having a cam thereon coöperating with the door, the collar on the arbor adapted to engage the casing, the spring for moving the collar longitudinally of the arbor and a removable operating device for the arbor adapted 75 to disengage the collar from the casing.

7. The combination with the casing having the aperture, and the door for closing it, of the arbor having the cams engaging the door, 80 the collar in the arbor, a spring for moving it longitudinally of the arbor and engaging devices between the collar and casing and the removable operating device for the arbor adapted to engage the collar to release it from 85 the casing.

8. The combination with the casing having the aperture and the door for closing it, of the arbor having the cam for engaging and operating the door and the angular portion, 90 the collar on the angular portion, the spring for operating the collar longitudinally of the arbor, and locking projections between the collar and casing for securing the arbor.

JOSEPH WARREN CUTLER.
